UNITED STATES PATENT OFFICE.

ROBERT J. WOOD, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING LOOSE MATERIAL.

Application filed June 2, 1921, Serial No. 474,431. Renewed May 4, 1925.

To all whom it may concern:

Be it known that I, ROBERT J. Wood, a citizen of the United States, residing at Chicago, in the county of Cook and State 5 of Illinois, have invented an Apparatus for Handling Loose Material, of which the following is a specification.

This invention relates to improvements in apparatus for handling loose material, 10 and more particularly to scraper devices adapted for transporting coal and the like from the working face of the mine to an entry for loading the mine cars.

The principal object of the present invention is to provide simple and more efficient means for changing the course of direction of the scraper. Other objects will appear from time to time as the description proceeds.

20 My invention may best be understood by referring to the drawings in which:

Figure 1 is a top plan view of the turning mechanism.

Figures 2 to 4 inclusive are diagrammatic 25 views illustrating the typical installation in a mine showing a scraper in various positions with respect to the turning mechanism.

Figure 5 is a view and elevation of the 30 turning mechanism in place in a mine.

Figure 6 is a detail.

Scrapers loading devices which have heretofore been used in mines usually include a scraper which is moved by means of flexible cables operated by a suitable hoisting engine. With devices of this character, however, it is often found necessary, on account of operating conditions, to change the direction of movement of the scraper 40 in moving it from the working face to the point of loading on the cars, and again in returning to the starting point. For instance, when such a device is used in the room and pillar system of mining, the 45 working face of the mine is usually at an angle to the direction of movement of the scraper toward the room entrance. As a large portion of the room is usually occupied with waste material or mine props, it is 50 necessary to direct the scraper first along the mine face and then in a path along one side of the room toward the room entrance. Heretofore the forward movement of the 55 scraper has been changed by providing one or more fixed sheaves adjacent the end of

the working face and adapted to be detachably engaged by the head rope or drag line of the scraper. The return or rearward movement of the scraper has been directed by a deflector or guide pulley positioned 60 near the point at which the scraper is turned in its forward movement.

In the drawings, the present invention is shown as applied to a typical mining operation of the room and pillar system, and 65 comprises a scoop or scraper 1 having a head rope 2 and a tail rope 3, each of said ropes being operated by a suitable hoisting engine, (not shown) usually situated at or outside of the entrance of the mine room. 70 A preferred construction of the scraper 1 comprises a body portion including upright side walls 1^A, 1^A converging at the rear of the scraper in a rounded end portion 1^B.

The working face 5 of the room is advanced longitudinally of the room as the mining operation proceeds. In the room illustrated, this face is formed substantially at right angles to the side walls 6 and 7, although it may be found preferable under 80 some circumstances to form the face at an obtuse angle to the side wall 7 nearest the room entrance, as will subsequently appear. The tail rope 3 is led around a stationary sheave 8 anchored in the far corner of the 85 room and from thence around suitable guiding sheaves to the hoisting engine. At the opposite corner of the room, but removed somewhat from the working face and wall 7, I provide a turning device 9, which comprises a plurality of arms at angles to each other pivotally mounted to swing substantially in a horizontal plane about a pivot 12. In a preferred form illustrated three 90 of such arms are provided, disposed at substantially equal angles of 120° to each other, and of the same length. For purposes of illustration in diagrammatical views these arms may be arbitrarily indicated by separate numerals such as 13, 14, and 15. Each 95 of the arms comprises an upper plate 16, and a lower plate 17 spaced laterally therefrom and connected by suitable spacing members 18, 18. A plurality of vertically disposed flanged anti-friction rollers 19, 19, 100 are mounted one upon each end of arms 13, 14 and 15. It will be noted in Figure 3, that the arms 13, 14 and 15 are so proportioned in length respective to the scraper 105 that when the forward end of the latter 110

comes into engagement with one of the arms, as for instance arm 13, the adjacent arm 15 is of sufficient length to engage one side of the scraper adjacent the rear end thereof, 5 as will hereinafter more fully appear in the description of the operation of the device.

A preferred means of securing the turning device in place comprises a screw-jack 20 having a spiked upper end adapted to 10 engage the mine roof in the usual manner, and a retaining member 21 at its lower end adapted to engage a base plate 22. Said retaining member is illustrated in Figure 6 and preferably comprises a pin 23, having 15 an upper end 24 adapted to fit into the lower end of jack 20, a flange 25, and a tapered lower end 26 adapted to extend through the retaining plate 22 into the mine floor. A bearing ring 27 fits over the lower end of jack 20, and rests on the flange 25 of pin 23 to provide a spacing element upon which the lower end 17 of the turning device rests. When in operation the retaining member 21 is fixed in place on the floor, and jack 20 is 25 secured therewith in a vertical position to form a pivotal bearing for the turning device 9 as shown.

The operation of my device is as follows:

When the scraper is in starting position 30 shown in full lines in Figure 2, the lead rope 2 is engaged about two of the arms of the turning device such as 13 and 14. When the pulling force is exerted on the lead rope I find that the turning device 35 maintains the position substantially as shown in Figure 2. That is to say, the head rope 2 may be moved about the anti-friction rollers at the end of two arms without turning the device about its pivot. From 40 the initial position the scraper moves along the mine face, gathers a load of coal and approaches the turning device until the scraper is brought into contact with the arm 13, as shown in dotted lines in Figure 2. A continued pull on the head rope 2 will swing 45 the turning device about its pivot causing the scraper to turn therewith as shown in Figure 3. As this turning movement takes place the arm 15, and the flanged portion 50 of its roller 19, are brought about into contact with one side of the scraper adjacent the rear end thereof, as shown in dotted lines in Figure 3, to assist and steady the scraper in its turning movement. The said 55 roller is thus brought into position to engage the tail rope 3 after the scraper is advanced in a changed direction. The turning device continues to pivot until the arm 14 is moved out of contact with the scraper 60 and draft rope, and the roller on arm 13 is brought into engagement with the tail rope 2 as shown in Figure 4, in which position the scraper is fully turned into line with the point of unloading and the scraper continues its movement in that direction.

To bring the scraper back to the starting point the operation is substantially the reverse of the above described movements, viz, the head rope 2 is released and the rope 3 is pulled so as to bring the scraper into 70 engagement with the arm 15 (see Figure 4), and to turn the scraper in the reverse direction to a position substantially parallel to the working face 5 as shown in Figure 2.

It has been before suggested that the 75 working face 5 may be formed at an obtuse angle to the side wall 7. Such an arrangement has been found to be more economical in many cases where mining operations permit on account of the increased length of 80 the working face afforded by this arrangement.

From the above description, it will be seen that as the working face 5 is advanced, the fixed sheave 8 and the turning device 9 will 85 be advanced accordingly, to transport the coal away from the face. The apparatus is easily put in place, and affords a continuous movement of the scraper both forwardly and backwardly about the turning device, 90 and minimizes the manual labor required for handling the draft ropes and scraper.

It will be understood that I have shown my improved apparatus as applied to one system of mining merely for the purpose of 95 illustration of its use, but that it is readily adapted to diversified uses for transporting material, as for instance in excavating and grading operation. Furthermore, I do not wish to be understood as limiting myself to 100 the construction of apparatus illustrated excepting as specifically defined in the appended claims.

I claim as my invention:

1. In a scraper apparatus, in combination with a scraper having two draft ropes for reciprocably operating the same, a rotatable turning device having three or more bearing members spaced apart, any two adjacent members being arranged to successively engage said draft ropes at both ends of said scraper. 105

2. In a scraper apparatus, in combination with a scraper having two draft ropes for reciprocably operating the same, a turning device mounted free to rotate on a vertical axis, and having a plurality of bearing members spaced apart, any two adjacent members arranged to successively engage said draft devices at both ends of said scraper. 115

3. In a scraper apparatus, in combination with a scraper having two draft ropes for reciprocably operating the same, a turning device free to rotate on a vertical axis and comprising a plurality of arms each provided with an anti-friction bearing member at the end thereof any two adjacent bearing members being arranged to successively engage the draft ropes at both ends of said scraper. 125

4. In a scraper apparatus, in combination with a scraper having two draft ropes for reciprocably operating the same, a turning device free to rotate on a vertical axis and comprising three equally spaced radial arms each provided with a vertically disposed anti-friction bearing member at the end thereof.
5. In a scraper apparatus, in combination, 10 a turning device, and a pivotal bearing therefor comprising a screw jack, a perforated plate, a flanged pin having one end adapted to fit in the lower end of said jack and the other end adapted to extend through 15 said plate, and an annular spacing member adapted to fit over the lower end of said screw jack to form a bearing for said turning device.
6. In a scraper apparatus, in combination 20 with a scraper having two draft ropes for reciprocably operating the same, a rotatable
- turning device having three or more bearing members spaced apart, any one of said members coacting with said scraper to move the following member into engagement with the side of said scraper adjacent the rear end thereof.
7. In a scraper apparatus, in combination with a scraper having two draft ropes for reciprocably operating the same, a turning device free to rotate on a vertical axis and comprising three equally spaced radial arms each provided with a vertically disposed anti-friction bearing member at the end thereof, any one of said arms adapted to 30 35 40 45 50 55 60 65 70 75 80 85 90 95 100 105 110 115 120 125
